UNITED STATES PATENT OFFICE.

FRANCES B. WADDELL, OF NEW YORK, N. Y.

CIGARETTE-WRAPPER.

1,289,975.

Specification of Letters Patent. Patented Dec. 31, 1918.

Application filed June 1, 1918. Serial No. 237,766.

To all whom it may concern:

Be it known that I, FRANCES B. WADDELL, a citizen of the United States, residing at New York, in the county of New York and State of New York, have invented new and useful Improvements in Cigarette-Wrap-
pers, of which the following is a specifica-
tion.

My invention relates to the manual mak-
ing of cigarettes and to special paper wrap-
pers to be employed for this purpose.

One of the difficulties in making one's own cigarettes is that the tobacco usually spills from the ends of the paper during the process of rolling, resulting in a thin, tapering end which can not be held conveniently by the lips. Moreover, if an extra quantity of tobacco is placed at the end intended for the mouth, the tobacco which can not be tightly packed comes out in the mouth and causes annoyance.

The principal objects of the invention are to enable the smoker who prefers to roll his own cigarettes to make them with at least one end, the end to be inserted in the mouth, of the substantial thickness and shape of the body of the cigarette, and in this respect equal to the machine-made article.

A further object is to enable the consumer to make a cigarette with a filled-up end from which the tobacco can not come out into the mouth.

A further object is to provide a cigarette paper or wrapper so constructed that a cigarette may be rapidly and easily rolled by hand so as to form a well-filled tobacco-tight end.

The invention consists in the novel construction and arrangement of parts of a cigarette wrapper and cigarette hereinafter described and claimed, and shown in the accompanying drawings, in which drawings:

Figure 1 is a view showing a single sheet of cigarette paper made in accordance with the invention, the parts being in position before placing tobacco upon the paper;

Fig. 2 is a perspective view showing the parts in the position to begin rolling the cigarette with the tobacco in place;

Fig. 3 is a similar view showing the completely rolled and finished cigarette; and

Fig. 4 is a similar view showing a pack of sheets with the parts in position they occupy in a book or folder.

Referring to the drawings, 10 represents the body portion of a cigarette sheet pref-

erably of paper as ordinarily used. At one end of the sheet, preferably near one of the lateral edges 11, I provide a closure tongue 12 extending in the direction of the length of the sheet and of such size and proportions as to constitute an end closure of the cigarette when rolled. This closure tongue is provided with perforations 13 to permit ready passage of air therethrough when smoking the cigarette.

Extending from the said tongue 12 is what may be termed a holding strip 14, which constitutes an important feature of the invention. This holding strip is made of such a length that when the closure tongue is in its final position, the strip will extend into proximity to the other end of the body portion. That is, the tongue being attached at the end 15 of the body portion, when the tongue is bent up and the holding strip is bent down along the body portion it will extend into proximity to the opposite end 16 of said body portion.

The body portion, closure tongue, and the holding strip are all formed of the same sheet and are integral as shown in the drawings. When the closure tongue is bent up just before inserting the tobacco, it bends along the dotted line 17 shown in Fig. 1.

The use of the cigarette wrapper is as follows:

The user holds the paper in his fingers as with the ordinary paper, the tongue being bent upwardly along the line 17 at right angles to the plane of the paper and the tobacco is then placed on the paper and distributed along its length. The holding tongue is then bent down upon the tobacco and its end 18 extends into proximity to the opposite end 16 of the paper where it is held by the fingers for the purpose of holding the tobacco in place and also holding the closure in the proper position. The parts are then in the position shown in Fig. 2, the tobacco being distributed along the paper, there being a full amount at the end against the closure tongue 12. The cigarette is then rolled and finished in the usual manner, the outer turn of the paper overlying the tongue and holding the parts securely in the desired relation. Owing to the thinness of the material, the base of the tongue where it joins the body portion readily accommodates itself to the bend of the upper portion when rolled, and a neat-appearing cigarette with a full and substantial mouth end is the re-

sult, and it will be observed that the tobacco will be prevented from coming out into the mouth of the user.

As above stated, the tongue and holding strip are integral with the body portion, and for the purpose of stacking the sheets the tongues are bent down upon the paper as shown in Fig. 4, so that a number of the sheets will be packed and occupy very little space.

I claim:—

1. A wrapper for hand-made cigarettes consisting of a body portion having at one end a closure tongue for that end of the cigarette, and a holding strip extending from said tongue into proximity to the other end of said body portion.

2. A wrapper for hand-made cigarettes consisting of a body portion having at one end a perforated closure tongue with a holding strip formed integral with the body portion, the end of said strip reaching into proximity to the other end of said body portion to be held by the fingers at that end.

3. A cigarette comprising a wrapper having a closure tongue extending across one end of the cigarette and integral with the wrapper and having a holding strip extending inside the wrapper from said tongue into proximity to the other end.

In testimony whereof I have hereunto set my hand.

FRANCES B. WADDELL.
